UNITED STATES PATENT OFFICE.

JAMES F. CYPHERS, OF BALTIMORE, MARYLAND.

RECTIFYING COLUMN.

Application filed October 6, 1923. Serial No. 667,040.

This invention relates to the structure of a self-cleaning rectifying column. In the ordinary column the plates frequently become uneven or sagged in some part, therefore by increasing the depth of liquid over the orifices in that part, leaving the vapors to go through the parts where less liquid is. The very least unevenness will mean an irregular exhausting of the vapors from the descending liquid because the vapors will always go through the orifices where the least liquid is located. When the vapors begin to concentrate in going through a few openings only, eddy currents occur and material deposits from the liquid and the apparatus may be clogged up. This same operation is seen in the action of a whirl-pool in the water as it deposits material around itself. One object of my invention is to provide a rigidly constructed column in which all the parts are firmly held, and they are held from the vibration which takes place when the boiling on the plates is violent, as well as being held level. The vibrations often fatigue the plates until they break, and I propose to do away with this objection by properly supporting the plates, which prevents the vibration. Another object of my invention is to provide a self-cleaning beer plate. The orifices in the ordinary beer plate are made by striking up tongue-shaped projections at an angle of about 30 degrees. Beginning at the points where the tongue joins the plate, material begins to collect on each side, between the tongue and the plate, and in time so much material is built up that the orifices are clogged and the plate loses its effectiveness. Or the orifices are sometimes simply small holes. These holes have to be small to keep the liquid from flowing through, and since they are small, they often clog up. In my plate the members are struck up as semi-cylindrical parts, consequently the angle where they join the plate is a right angle, and a right angle connection causes the least deposit. Also, vapors continually blow through the entire opening nearly parallel to the plate and thus set up a scouring action and the holes, and the rest of the plate around the holes, are therefore kept practically clean. From the point of view of the liquid on the plate, this scouring action of the vapors acts as an agitator for the liquid. This agitation pre-

vents sediment held in suspension from falling out of the liquid and consequently, the action of the vapors is double, one cleansing and the other, preventative of the collection of sediment.

Still another object of my invention is to provide a long straight weir projecting down adjacent to the next lower plate, thus making a long overflow surface and also dispensing with the usual down pipes which also often become clogged. The lower end of the weir projects into the liquid on the lower plate and thereby forms a liquid seal, preventing vapors from coming up where the liquid has run down. The material falls from the weir in a thin sheet, or layer. There is so much material held in suspension in the initial purifying stages of beer, and similarly purified liquids that it is very desirable to make the parts so that there is little tendency for sediment to collect or fall out of suspension.

Further objects and advantages of my invention will be apparent from the following detailed description thereof.

While my invention may be carried out in many different ways, for the purpose of illustration, I have shown only one form of apparatus in the accompanying drawings, in which:

Figure 1 is a plan view of a rectifying column section, Figure 2 is a partial vertical view, with part of the casing of the front part of the column removed, and with certain other parts shown in section. Figure 3 is an enlarged perspective view of part of the self-cleaning plate.

Similar numerals refer to similar parts throughout the several views.

The column section 1 has flanges 11 by which the several sections are riveted or bolted together. In the column, and fastened to its sides are beer plates 2. These plates have struck-up semi-cylindrical members, the ends of which are open, forming vapor orifices. The vapors coming from the orifices cause the material on the plate to wash back and forth on the plate, and scour or loosen material which may have fallen out of suspension. Also, the moving vapors agitate the liquid on the plate, thus tending to keep the solids in suspension in it. At the edge of each plate is a straight weir 3 over which the material flows to the plate below. This weir, being straight, does not clog as the usual pipes do. The weir ex-

tends to the column sides and down adjacent to the next lower plate, and there it acts as a distributor to spread the material over that plate and it also forms a liquid seal to prevent vapors from coming up.

The portion of the plate directly beneath the weir and onto which the material flows, has no orifices, as shown in Fig. 1. The material coming down in a sheet tends to wash out any sediment which collects at this point.

The plates are rigidly supported on beams 4 and 5, which beams are attached to wings on the upper part of post sections 6, 7 and 8.

15 The post structure herein is similar to that shown in my copending application for a patent for improvements in "rectifying columns," Serial No. 666,211, filed October 2, 1923.

20 The posts are made up in sections with internal and external screws at their respective ends. Short nuts 9 are placed over the external screws before the next post section is screwed on. The upper sections, 8, 25 have tapering nuts 10, over which the sockets in the lower posts of the next column section fit.

These columns are self-cleaning, and yet, should extra cleaning or repairs be necessary, manholes 12 are provided in the casting above each plate for that purpose. These manholes are kept closed when the column is in use.

Figure 3 shows practically a full sized view of a portion of the plate and its orifices. The members are struck up in staggered rows, so that the vapors from one row have a greater surface over which to agitate the material on the plate with a minimum of interference from the vapors coming from the opposite row of members. By means of this staggered row arrangement, the material is kept in motion over the whole plate area, and it is positively agitated around the orifice outlets.

Since the plates are self-cleaning and the down-pipes are eliminated and their place taken by long straight weirs which do not cause deposits from the material, and since the plates are kept level by the supports, thus causing even vapor action over the entire plate, it is apparent that the column can be practically continuous in its operation, and will but rarely need to be stopped for cleaning.

The operation of my invention will be apparent from the foregoing description.

Although I have described my invention as a rectifying column for alcohol purification, it may be used to separate any two liquids where one is more volatile than the other and where the liquids contain material held in suspension, or other thick substances which would clog a tube and bonnet rectifying column. When I have used

"beer plate" I mean a plate which is used as a beer plate, but I do not intend, especially in the following claims, to limit the plate to that use.

The semi-cylindrical form of the struck-up parts is used for illustration only, for any several faced prismatic form for the struck-up parts would produce approximately the same results. I, therefore, consider my invention to include all equivalents within the scope of the following claims.

Many changes in the apparatus may be made without departing from the spirit of my invention.

I claim:

1. In a rectifying column, substantially horizontal superposed plates to hold material to be rectified, means on said plates to admit and cause the incoming vapors to constantly agitate the materials on said plates, sectional posts supporting said plates, plate-supporting beams between and attached to said posts, the sections of said posts being rigidly connectable with each other.

2. A self-cleaning beer plate comprising a plate having a plurality of hollow projecting semi-cylindrical members, a straight line in the curved surface and passing from end to end of each of said members being substantially parallel to said plate, and open ends in said members to form vapor orifices.

3. A self-cleaning beer plate having an elongated opening therein, a hollow orifice member having sides projecting upwardly from said plate substantially at right angles and on opposite sides of said opening, said orifice member being open at one end substantially the width of said member between said sides, a cover over the opening in said plate between and joining said sides and removed from said plate, said cover being substantially parallel to said plate adjacent the open end of said orifice member.

4. A self-cleaning beer plate having an elongated opening therein, a hollow orifice member having sides projecting upwardly from said plate substantially at right angles and on opposite sides of said opening, said orifice member being open at each end substantially the width of said member between said sides, a cover over said first named opening between and joining said sides and removed from said plate, said cover being substantially parallel to said plate adjacent the open ends of said orifice member.

5. In self-cleaning beer plate adapted to hold material to be rectified, projecting covered members in said plate having two vapor outlet orifices between and adjoining said plate and the walls and tops of each of said members, said projecting members being adapted to cause the vapors coming

through said orifices to agitate the material on said plate.

6. A self-cleaning beer plate comprising a plate having a plurality of hollow projecting prismatic members longitudinally substantially parallel to said plate, and open ends in said members to form vapor orifices.

7. A self-cleaning beer plate comprising a plate having a plurality of hollow projecting prismatic members longitudinally substantially parallel to said plate, arranged in staggered relation to each other, and open ends in said members to form vapor orifices. ¹⁰

JAMES F. CYPHERS.
